UNITED STATES PATENT OFFICE.

WEBSTER C. ESTES, OF NEW YORK, N. Y.

DESIGN FOR A WOODEN JAR.

SPECIFICATION forming part of Design No. 28,637, dated May 17, 1898.

Application filed April 12, 1898. Serial No. 677,375. Term of patent 14 years.

To all whom it may concern:

Be it known that I, WEBSTER C. ESTES, a citizen of the United States, residing at New York, (Brooklyn,) in the county of Kings and State of New York, have invented and produced a new and original Design for a Wooden Jar, of which the following is a specification, reference being had to the accompanying drawings, in which—

10. Figure 1 is an elevation. Fig. 2 is a plan, and Fig. 3 a vertical section.

The general configuration of the jar is cylindrical; and the leading features of my design consist in the slightly-convex top merging into a rounded edge and the adjacent semi-elliptical cove at the upper end of the cylindrical body.

The design of the jar comprises the parallel sides *a*, the slightly-convex top *b*, merging into the rounded edge *c*, the semi-elliptical cove *d* 20 at the upper end of the cylindrical body, and the lower edge *e* is usually rounded.

What I claim is—

The design for a wooden jar, substantially as shown and described. 25

Signed by me this 9th day of April, A. D. 1898.

WEBSTER C. ESTES.
